UNITED STATES PATENT OFFICE.

HARRY D. MURRAY, OF GROVE CITY, PENNSYLVANIA.

GAS-ENGINE-CONTROL MECHANISM.

Application filed September 22, 1924. Serial No. 739,149.

Gas engines, especially such as are used in oil and gas well operations, are so arranged as to be conveniently subjected to manual control for the drilling operation and for automatic control in the use of the engine in pumping the well, or after the drilling is completed. In the present invention a convenient throttle actuating mechanism and speed sensitive mechanism are combined. It is further desirable in combination with a gas mixer valve to have a bypass of sufficient capacity to keep the engine operating after the throttle valve is closed and the present invention involves a means by which this may be accomplished. The throttle in a gas engine is rather sensitive for starting and usually starts best with a given throttle. The present invention involves a means for indicating the throttle opening so that it may be nicely adjusted particularly for the purpose of starting and also for running conditions if desired. The invention also involves improvements in the speed sensitive mechanism particularly adapting it to this type of engine and for use in connection with a throttle.

The invention is illustrated in the accompanying drawings as follows:—

Fig. 1 shows a central section through the air and gas mixing valve and the throttle and governor.

Fig. 2 a section on the line 2—2 in Fig. 1.

Fig. 3 a section on the line 3—3 in Fig. 1.

Fig. 4 a section on the line 4—4 in Fig. 1.

Fig. 5 an end view of the throttle operating wheel and setting indicator.

Fig. 6 a section on the line 6—6 in Fig. 1.

1 marks the controlling and throttle valve body, 2 a pipe connecting this body with a gas ring 3 of the air and gas mixing valve 4. The gas and air mixing valve is of the ordinary construction comprising the gas ring 3 and the air inlet pipe 4^a. Gas inlet ports 3^a lead from the gas ring. Air ports 4^b lead from the air passage and these are controlled by plates 4^c, thus delivering air and gas through the same general mixing valve to a cylinder 4^d. Thus gas is admitted through the valve 4 by way of the ring and air is admitted to parts of the valve within the ring, these being properly proportioned for the purposes of the engine, the amount of gas being varied to within the range of explosive mixture to vary the power of the engine.

The controlling valve body 1 has a diaphragm 5 in which is arranged a valve seat 6. A governor valve 7 operates on this seat.

Gas is delivered to the governor valve body through a pipe 8 and to a chamber 9 from which the throttle valve passage 10 communicates to the governor valve chamber 7^a, the gas ordinarily passing by the governor valve in accordance with the requirements of the engine. A throttle valve seat 11 is around the passage 10 and is operated upon by a throttle valve 12. A screw-threaded stem 13 extends from the valve 12 and an operating wheel 14 is secured to the stem. A cable 15 operates on the operating wheel and runs to some desired point of control. The operating wheel 14 has graduations 16 thereon and a point 17 is arranged near the wheel so that the position of the wheel may be readily ascertained and thus the opening of the throttle indicated.

A bypass opening 18 extends from the inlet chamber 9 to the control valve chamber 7^a so that when the throttle is closed this bypass delivers gas sufficient to maintain the engine running in idling condition, the amount of gas delivered being proportioned to the air going through the mixer valve to maintain an explosive mixture. The bypass may be adjusted by a needle valve 18^a. A flange 19 is arranged on the upper part of the body and this is provided with a cover 20. A cover frame 21 is mounted on the flange 19 and secures the cover plate in place. A valve stem 22 extends through the cover plate and is provided with a head 23. A spring 24 is tensioned between the head and an adjusting nut 23^a on the cover 20. It is of such strength as to practically balance the valve against the effect of the ingoing gas, the preponderance being slightly in favor of the spring in order to maintain the valve in open position when the valve is not influenced by the governor. In order to adjust the spring for different pressures of gas a nut 23^a may be adjusted to give the spring tension to accomplish this purpose.

Mountings 25 are arranged on the frame 21 and carry a shaft 26, this shaft being locked with the mounting by a set screw 27. A pulley 28 is driven by the engine (not shown) supplied by the mixing valve, the power being communicated by a belt indicated at 29 in Fig. 4. A governor head 30 is secured to the pulley and governor weights 31 are pivotally mounted on the head by means of pins 32. The governor weights have the inwardly extending bell crank arms 33 which engage a sliding sleeve 34. The sliding

sleeve is locked to rotate with the head by a pin 35. A spring 36 is arranged within the sleeve and operates against a collar 37, the spring 36 forming the centripetal element of 5 the governor and the weights the centrifugal element. The collar 37 is locked to rotate with the sleeve 34 by means of a pin 38. A stop cam hub 39 and a thrust screw 40 is screwed onto the shaft against the hub and 10 through the hub operates on the collar 37 to vary the tension of the spring 36. The screw has the grooves 41 into which the lock screws 42 extend for locking the screw 40 in adjustment. The shaft has the oil openings 15 43 and 44 by means of which the different members journaled on the shaft may be lubricated. The sleeve 34 has a groove 45 and a yoke 46 is mounted in this groove. A lever 48 is pivotally connected with the yoke 46. 20 The lever is pivotally mounted on a pin 49 between uprights 50 extending upwardly from the frame. The lever has a bell crank arm 51 which is in position to engage the valve stem head 23 and to depress and close 25 the valve as the governor sleeve 34 is forced sidewise by the opening weights through the arm 33. The governor operates in the manner of the ordinary centrifugal governor, the spring 36 operating against the weights and 30 these varying in position as the centrifugal force due to the rotation of the weights varies, this difference being communicated through the leverage to the valve closing the valve or permitting it to open in accordance 35 with the speed.

The safety stop hub 39 has a safety cam 52 and as the cam is rotated operates upon the stem head 23 to close the valve. A lever 53 extends from the hub 39 and is provided 40 with a pulley 54 which normally rides on the belt 29. Upon the breaking of the belt and the dropping of the lever 53 the cam operates to close the governor valve and shut down the engine.

45 What I claim as new is:—

1. In a gas engine control mechanism, the combination with a valve body; an unbalanced governor valve mounted in the body; a spring tending to open the valve and balancing the same against fuel pressure to relieve the governor of the gas and spring load; and a speed sensitive device operating to close the valve.

2. In a gas engine control mechanism, the combination with a valve body; an unbalanced governor valve mounted in the body; a spring tending to open the valve and balance the valve against fuel pressure to relieve the governor of fuel pressure and spring load; a speed sensitive device operating to close the valve; and means for adjusting the spring for different gas pressures.

3. In a gas engine control mechanism, the combination of a valve body having a control valve chamber; an inlet chamber; an un-

balanced governor valve controlling the discharge from the control chamber; a throttle valve controlling the communication between the inlet chamber and the control chamber and having its axis at an angle to the axis of the governor valve; a spring on the governor valve tending to open the governor valve and balancing the same against fuel pressure to relieve the governor of fuel pressure and spring load; and a speed sensitive device closing the governor valve as the speed increases.

4. In a gas engine control mechanism, the combination of a valve body having a control valve chamber; an inlet chamber in the body; an unbalanced governor valve controlling the discharge from the control chamber; a throttle valve controlling the communication between the inlet chamber and the control chamber, said throttle valve having its axis at an angle to the axis of the governor valve; a spring on the governor valve tending to open the governor valve and balancing the same against fuel pressure to relieve the governor of fuel pressure and spring load; a speed sensitive device closing the governor valve as the speed increases; and a bypass between the inlet chamber and the controlling valve chamber.

5. In a gas engine control mechanism, the combination of a control valve; a governor frame; a shaft fixed in the shaft; a governor head mounted on the frame; governor weights carried by the governor head; a sleeve mounted on the shaft and actuated by the governor weights; a spring within the sleeve resisting the movement of the sleeve; and a lever communicating the movement of the sleeve to the valve.

6. In a gas engine control mechanism, the combination of a control valve; a governor frame; a shaft fixed in the shaft; a governor head mounted on the frame; governor weights carried by the governor head; a sleeve mounted on the shaft and actuated by the governor weights; a spring within the sleeve resisting the movement of the sleeve; a spring tending to open the governor valve; and a lever communicating the movement of the sleeve to the governor valve to close the same.

7. In a gas engine control mechanism, the combination of a control valve; a governor frame; a shaft fixed in the frame; a governor head mounted on the frame; governor weights carried by the governor head; a sleeve actuated by the governor weights; a spring within the sleeve resisting the movement of the sleeve; a stem on the valve; a spring tending to open the valve; a lever mechanism communicating the movement of the sleeve to the stem to close the valve; and a safety stop operating on the stem to close the valve.

8. In a gas engine control mechanism, the combination of a valve; a frame; a stationary shaft mounted in the frame; a governor head

5 rotatively mounted on the shaft; a sleeve slid-
ingly mounted on the shaft; means for lock-
ing the sleeve rotatively with the head; gov-
ernor weights carried by the head and com-
municating a movement of the sleeve; a
10 spring resisting the movement of the sleeve;
means communicating the movement of the
sleeve to the valve; and means for introduc-
ing lubrication for the head through the shaft.
15 9. In a gas engine control mechanism, the
combination of a valve; a frame; a stationary
shaft mounted in the frame; a governor head
rotatively mounted on the shaft; a sleeve slid-
ingly mounted on the shaft; means for lock-
15 ing the sleeve rotatively with the head; gov-
ernor weights carried by the head and com-
municating a movement of the sleeve; a
spring resisting the movement of the sleeve;
means communicating the movement of the
20 sleeve to the valve; and a nut operating on
the shaft for adjusting the spring.

10. In a gas engine control mechanism,
the combination of a valve; a frame; a shaft

25 mounted on the frame; a governor head
journaled on the shaft; a sleeve journaled on
the shaft, said sleeve having a groove; gover-
nor weights carried by the head and operating
on the sleeve; a yoke journaled in the groove;
30 and a lever pivotally connected to the yoke
communicating the movement of the sleeve
to the valve.

11. In a valve mechanism for gas engines,
the combination of a valve body having a
controlling valve seat and a throttle valve
seat, the axis of said seats being at right an-
gles to each other; a controlling valve operat-
ing on the controlling valve seat; a throttle
35 valve comprising a head opening and closing
by a movement toward and from said throttle
valve seat; and a bypass delivering gas past
the throttle valve when closed to provide the
40 engine with an idling supply.

In testimony whereof I have hereunto set
my hand.

HARRY D. MURRAY.
